UNITED STATES PATENT OFFICE.

THOMAS J. WINANS, OF BINGHAMTON, NEW YORK, ASSIGNOR TO THE
NINETEEN HUNDRED WASHER COMPANY, OF BINGHAMTON, NEW
YORK.

OPERATING MECHANISM.

No. 841,606.

Specification of Letters Patent.

Patented Jan. 15, 1907.

Application filed April 12, 1906. Serial No. 311,273.

To all whom it may concern:

Be it known that I, THOMAS J. WINANS, a citizen of the United States, residing at Binghamton, in the county of Broome and State 5 of New York, have invented certain new and useful Improvements in Operating Mechanisms, of which the following is a specification.

My present invention relates to improvements 10 in operating mechanisms, and has for its object the provision of machinery and devices for receiving and transforming a rotary motion of some of its parts into an oscillating or reciprocating motion of some of the other 15 parts of the machinery.

A further object is to improve the machinery in certain particulars and arrangements and to provide spring-cushions to take up the shock of the motions of parts of the 20 machinery to prevent jarring to the oscillating parts of the machinery and wear on the same.

The invention consists in certain combinations and arrangements of rotating mechanism 25 and in certain combinations and arrangements of oscillating devices so connected that the rotary motion received by the rotating mechanism is transferred to and transformed into the oscillating motion of 30 the latter mechanism.

In the accompanying drawings I have illustrated one example of the physical embodiment of my invention, illustrated as applied to a washing-machine for clothes and 35 constructed according to the best mode I have so far devised for the practical applications of the principle of the invention.

Figure 1 is a view in side elevation of my 40 operating mechanism, illustrated in combination with a clothes-washing tub. Fig. 2 is a plan view of the oscillating mechanism, showing the rotary shaft and parts of the frame in section. Fig. 3 is a vertical central section of the oscillating mechanism, some 45 parts being in full lines. Fig. 4 is a bottom plan view of parts of the oscillating mechanism. Fig. 5 is a perspective view of a portion of the oscillating shaft and a member thereon for imparting motion to the oscillating 50 devices or machinery. Fig. 6 is a perspective view of one of the members of the oscillating mechanism. Fig. 7 is a sectional view taken in the direction and looking at the parts indicated by arrows in Fig. 2. Fig.

8 is a vertical central sectional view of the 55 rotating mechanism of the machine, and Fig. 9 is a sectional view on line 8 8 in Fig. 8.

Referring to the drawings, the numeral 1 designates a stand or table forming a support for the machinery; 2, the legs of said table; 60 3, a horizontal frame-piece secured to the table or stand; 4, a similar piece at right angles to the piece 3; 5 and 6, upright frame-pieces, and 7 an upper horizontal frame-piece, the before-mentioned pieces forming a substantial 65 and rigid frame for the support of the machinery.

The sectional casting 8 is supported by and connects the frame-pieces 6 and 7, said casting forming a casing for the gear-wheels contained therein and provided with two flanges 8' and 9, which are connected by bolt 10 with the metallic plates 11 on the horizontal frame-piece 7. Within the casing 8 the transverse shaft 12 is journaled, and said 75 shaft carries a driven pulley 13, which pulley may be driven by a water-motor. The shaft 12 is not journaled directly in the casing 8, but has its bearings in a cam-sleeve or eccentric bearing-bar 14, and the bar or sleeve 14 80 is in turn journaled in the walls of the casing 8 and rotates freely therein, the shaft 12 being of course free to rotate in the sleeve or hollow bar 14. As seen clearly in Fig. 9, the shaft 12 is located eccentrically in the bearing- 85 sleeve 14, and at the bifurcated end 14' of the bar a lever 15 is pivoted at 16. A spring 17 is seated within a recess in the bar 14 and bearing against the end of the lever 15 tends to press it outwardly. By means of this lever 90 the hollow bar or sleeve 14 may be turned in its bearings for a purpose to be described and when so turned may be located in adjusted position by the lug 18, which enters either of the two openings 19 or 20 in the cas- 95 ing.

A worm-gear 21 is formed rigid with the shaft 12, and this worm in the positions shown in Figs. 8 and 9 is in mesh with a horizontal gear-wheel 22, rigid and rotatable with 100 the vertical shaft 23. This shaft 23 is supported in bearings 24 and 25, which are secured by bracket-arms to the upright frame-piece 6 and also has bearings in the casting 8. Thus by means of the driven pulley 13 the 105 shaft 23 is rotated through the medium of the shaft 12, worm 21, and gear-wheel 22. Above the worm-gear and gear-wheel and

journalized in the casting 8 I locate a transverse shaft 24', upon which is mounted the vertical gear-wheel 25'. A second gear-wheel 26 is located at the end of the shaft 24', and wheel 6 meshes with the gear-wheel 27 on driven shaft 28. Assuming the hollow bearing-bar 14 to be in the position shown in Fig. 9, if the handle or lever 15 be turned to vertical position so that the lug 18 engages opening 20, Fig. 1, the worm-gear is disengaged from the gear-wheel 23 and made to mesh with the teeth of the vertical gear-wheel 25'. In this position of the eccentric hollow bearing-bar the rotary motion of the driven pulley is transmitted through the worm-gear, gear-wheel 25, shaft 24', gear 26, gear 27, and shaft 28, thus driving the shaft 28 and operating said shaft for any desired purpose—as, for instance, a clothes-wringer.

At its lower end the vertical rotary shaft 23 is provided with a crank-piece 29, clamped thereon by means of the bolt or screw 30. A connecting-rod 31 connects the crank-arm 29 with a lever-arm 32, loosely mounted on the vertical pintle 33. This pintle 33 is supported and adapted to partially rotate in a bearing-piece 34, which is in turn supported centrally of the stand or table 1. Upon the pintle and located above the lever-arm 32 is mounted a triangular-shaped plate 35, which plate is rigidly secured to the pintle or post 33 and turns therewith, and above the plate 35 a second similarly-shaped plate 36 is loosely mounted on the pintle. A spider for supporting the vessel or receptacle to be oscillated is composed of the three arms 37, 38, and 39, and these three arms are held between the clamp-plates 35 and 36 by the clamping-nut 40. As clearly shown in Fig. 7, the spider-arm 39 is directly connected by a spring 41 to the lever-arm 32, and the lever-arm 32 being in turn connected with the rod 31 it will be understood that the spider is oscillated by the movement of rod 31, the spring 41 making a flexible or cushioning connection between the arm and spider, but such a connection as will give sufficient direct impetus to the spider in order to impart a swinging or oscillating movement thereto on the pintle or post 33.

The spider-arms are held rigid with the pintle or post by means of the two triangular clamp-plates and the clamping-nut 40, as described. Thus when the rotary motion of the crank-arm 29 is transformed into a reciprocating motion of the rod 31 said rod swings the lever-arm 32, which is loose on the shaft or pintle, and the spring 41, being under high tension, imparts the swinging or oscillating motion to the spider with an easy start and reverse. To further cushion the devices as they start and reverse in their oscillation, I provide an obstruction piece or plate 42, which is mounted loosely on the pintle 33 and suspended at either end by the springs 43 and

44, which springs are respectively hooked over the brackets 45 and 46, secured to the frame-piece. As more clearly shown in Fig. 4, this obstruction-plate 42 is provided with a pair of shoulders 48 and 49, located at the ends of an arc of a circle having the pintle 33 as its center. On the under side of the rigid clamp-plate 35 a depending lug is formed, preferably integral therewith, and this lug, projecting downwardly through the slot or opening 51 in lever-arm 32, is in position to swing backward and forward with the oscillation of the clamp-plate and spider. Now as the spider swings or oscillates with the pintle 33 as a center at the extreme of its swinging movements the lug 50 comes in contact with one or the other of these shoulders 48 or 49, and as the plate 42 is suspended by the springs, as before described, the motion of the spider as it stops is not only cushioned by the elasticity of the springs, but the motion of reversing and starting in the reverse direction is assisted by the tension of the springs, thus providing a forward - and - backward swing motion about the center of the mechanism without shock or jar and avoiding all jerks of the mechanism.

In operation, assuming the mechanism to be in the positions illustrated in the several figures, the pulley 13 is driven by suitable power, and through the medium of the worm wheel or gear 12, gear-wheel 22, and shaft 23 the crank-arm is horizontally rotated, which reciprocates the rod 31, and this rod in turn imparts the swinging or oscillating motion to the spider through the connections described, the springs acting to take up all lost motion and prevent shocks or jars in the operation of the device.

From the above description, taken in connection with the drawings, it becomes evident that I have produced a mechanism which fulfills all the conditions set forth as the purpose or objects of the invention, providing an easy-running and efficient machinery for the purposes set forth.

Having thus fully described my invention, what I claim as new, and desire to secure by Letters Patent, is—

1. The combination in a mechanism as described of a supporting-frame, a post in said frame, a spider connected to and adapted to swing with said post as a center, a lever-arm connected with the swinging spider and a spring interposed between said spider and lever-arm.

2. The combination in a mechanism as described of a supporting-frame, a post in said frame, a spider connected with said post, a lever-arm and spring connection between said arm and spider, and means for absorbing the momentum in one direction and returning an impulse in the opposite direction as the spider is reversed in its movement.

3. The combination in a mechanism as de-

scribed of a frame, a spider supported therein and adapted to swing in a horizontal plane, a lever-arm, a spring connecting said lever-arm with the spider, means for moving said lever-arm, and a pair of springs with connections to the spider for absorbing the momentum in one direction and returning an impulse in the opposite direction as the spider is reversed in its movement.

10 4. The combination in a mechanism as described, of a frame, a spider supported therein and adapted to swing in a horizontal plane, a lever-arm for operating said spider, and an elastic connection between said arm and 15 spider; and means for absorbing the momentum in one direction and returning an impulse in the opposite direction as the spiders reversed in its movement.

5. The combination in a mechanism as described, of a spider suitably supported and adapted to swing in a horizontal plane, elastic connections for operating said spider; and elastic means for absorbing the momentum in one direction and returning an impulse in 25 the opposite direction as the spider is reversed in its movement.

6. The combination with a frame, of a pintle supported therein, a spider clamped to said pintle by clamp-plates, a lever-arm, a 30 spring connecting said lever-arm and spider, a plate having bearing on the pintle and springs connecting its ends with the frame, and means on the spider in connection with said last-named springs for absorbing the 35 momentum and cushioning the movement of said spider.

7. The combination with a supporting-frame, of a post, a spider secured thereon, a lever-arm having elastic connection with 40 said spider; an obstruction-plate, springs connecting the ends of said plate with the frame, the spider having a lug adapted to engage said obstruction-plate to absorb the momentum and cushion the movement of the spider.

45 8. The combination with a supporting-frame, of a post, a clamp-plate rigid with said post, an upper plate, spider-arms having their ends held between said plates and a clamping-nut for securing said spider ends; a lever-arm; and a spring connecting said lever-arm and one of the spider-arms, and means for operating said lever.

9. The combination with a frame, of a post supported and rotatable therein, a plate rigid 55 with said post, a clamp-plate and spider-arms interposed between said plates and a clamping-nut for securing these members, a lever-operating arm having elastic connection with one of said spider-arms; means for 60 operating said lever, and means to absorb the momentum and cushion the movement of the spider.

10. The combination with a frame, of a post rotatably supported therein, a plate 65 rigid with the post, a clamp-plate, spider-arms

interposed between said plates and a clamping-nut for securing these members, a lever-arm, and a spring connecting said arm and one of the spider-arms; an elastic obstruction-plate and means on the spider for engagement with said plate to absorb the momentum and cushion the movement of the spider.

11. The combination with a frame of a post rotatably supported therein, a plate rigid with the post, a clamp-plate on the post, 75 spider-arms interposed between said plates and a clamping-nut for securing these members, a lever-arm, a spring connecting said arm and one of the spider-arms, an obstruction-plate, springs anchoring said plate to 80 the frame, the spider having a lug for engagement with said obstruction-plate.

12. The combination with a supporting-frame, of a post rotatably mounted therein, a spider on said post, a lever-arm having elastic 85 connection with said spider, a reciprocating rod connected with said lever-arm, a crank and shaft connected to said rod, and means for imparting a rotary motion to said shaft.

13. The combination with a supporting-frame, of a post rotatably mounted therein, a spider on said post, a lever-arm having elastic connection with said spider, a reciprocating rod connected with said lever, a crank and shaft connected to said rod; means for imparting a rotary motion to the shaft; and elastic 95 means for absorbing the momentum and cushioning the movement of the spider.

14. The combination with a supporting-frame and a support adapted to swing about 100 its center, of a rotary shaft and connections therefrom for transforming its rotary motion into a swinging motion of the support, a gear-wheel on said shaft, a transverse shaft having a worm-gear thereon meshing with 105 said gear-wheel, and means for rotating said transverse shaft.

15. The combination with a supporting-frame and a support adapted to swing about 110 its center, of a rotary shaft and connections therefrom for transforming its rotary motion into a swinging motion of the support, a gear-wheel on the shaft, a transverse shaft having a worm-gear thereon, and means for throwing 115 said worm-gear and gear-wheel into and out of engagement.

16. The combination with a supporting-frame and a support adapted to rotate about 120 its center, of a rotary shaft and connections therefrom to transform the rotary motion into a swinging motion of the support, a gear-wheel on the shaft, a transverse shaft having a worm-gear thereon, an eccentric-bearing for 125 said transverse shaft, and a spring-pressed lever for throwing said worm-gear and gear-wheel into and out of engagement.

17. The combination with a supporting-frame and a support adapted to rotate, of a rotary shaft and connections therefrom for transforming its rotary motion into an alter- 130

nating swinging motion of the support, a gear-wheel on the shaft, a transverse shaft and a worm-gear thereon, a bearing-sleeve, and said transverse shaft located eccentrically in said sleeve, and a spring-pressed lever for throwing said worm-gear and gear-wheel into engagement.

In testimony whereof I affix my signature in presence of two witnesses:

THOMAS J. WINANS.
